SPARKING PLUG

Gustav Ruthardt, Stuttgart-Zuffenhausen,
GermanyApplication September 25, 1935, Serial No. 42,934
In Germany October 8, 1932

1 Claim. (Cl. 123—169)

This invention relates to spark plugs with a hollow body defining a central longitudinal passage for the reception of a central electrode and tips, and with inwardly extending projections which subdivide the passage into a plurality of combustion chambers of alternately increasing and decreasing cross-sectional area, for effecting a more thorough churning, and consequently a more complete combustion of the mixture in the passage.

It is an object of the invention to provide an improved spark plug of this type.

To this end, a helical groove is made in the walls of the combustion chambers.

The helically shaped grooves in the double conical combustion chambers impart to the jet of burning gases the direction of a spreading or point flame after the ignition of the mixture.

The sparking plug is intended to ensure a smooth running of the engine free from knocking, even when employing a so-called poor mixture. Even in the case of high compression engines the spark plug can be employed with inferior fuel mixtures, such as gas oil, spirit mixtures and the like, without detrimentally affecting the output and the life of the engine.

An embodiment of the invention is illustrated

by way of example in the accompanying drawing.

The spark plug body *a* has a central longitudinal passage. Several conical narrowings and widenings *b* are provided in this passage. In the walls of the double conical combustion chambers of alternately increasing and decreasing cross-sectional area are formed by the narrowings and widenings of the passage. Helical grooves *d* are formed in the walls of the combustion chambers for the purpose specified. The tips *c* are fixed in the wall of the body *a* at the upper end of a screw-threaded extension portion. The ends of the tips *c* are bent into the combustion chamber surrounding the central electrode *e*.

I claim:—

A sparking plug for internal combustion engines, comprising in combination a hollow sparking plug body, mass-electrodes and a central electrode in said body, said body having a passage extending to said electrodes and composed of a plurality of alternate conically widening and narrowing sections, and having a helical groove formed in the conically widening and narrowing sections of the passage.

GUSTAV RUTHARDT.
